UNITED STATES PATENT OFFICE

BYRON H. ABERT, OF MILWAUKEE, WISCONSIN

SAFETY-VALVE ATTACHMENT FOR DENTAL VULCANIZERS

Application filed September 27, 1926. Serial No. 138,032.

This invention relates to improvements in safety valve attachments for dental vulcanizers.

Dental vulcanizers are provided with safety valves which automatically open when the steam pressure within the vulcanizer becomes too great. The heating medium remains in operation, however, with the result that any work within the vulcanizer is destroyed by the dry heat.

It is, therefore, the primary object of the present invention to provide an attachment for a dental vulcanizer which utilizes the force of the escaping steam from the safety valve to operate a lever, the lever operating to shut off the heating element.

A further object of the invention is to provide an attachment of the class described which will protect articles in the process of vulcanization from being destroyed by dry heat after the safety valve blows.

A further object of the invention is to provide a safety valve attachment for dental vulcanizers which will permit the safe control of vulcanization, after, as well as during working hours without direct personal attention.

A further object of the invention is to provide an attachment of the class described applicable to vulcanizers in which the heating element is supplied with gas.

A further object of the invention is to provide a safety valve attachment for dental vulcanizers which is of very simple construction, is automatic in operation, is easily installed, is strong and durable and is well adapted for the purposes described.

With the above and other objects in view the invention consists of the improved safety valve attachment for dental vulcanizers, and its parts and combinations as set forth in the claims and all equivalents thereof.

In the accompanying drawing in which the same reference characters indicate the same parts in all of the views:

Fig. 1 is a view of the upper portion of a dental vulcanizer showing the improved safety valve attachment installed thereon;

Fig. 2 is a plan view partly in section of the attachment and on a larger scale; and

Fig. 3 is an enlarged detail view of a lever arm forming part of the device.

Referring now more particularly to Figs. 1 and 2 of the drawing it will appear that the numeral 5 indicates a dental vulcanizer of ordinary construction in which the heating element is supplied with fuel in the form of gas by a tubing or hose 6 which passes over the upper portion of the vulcanizer and adjacent the lever arm 7 thereof.

The safety valve attachment comprises a bracket portion 8 having a U-shaped clip portion 9 to fit over and engage the lever arm 7 of the vulcanizer. Upstanding from the medial portion of the bracket portion is a plate 10 to which is pivotally secured a weighted arm 11 having an enlarged end portion 12, limited in movement in one direction by a lug 13 projecting from the side of the plate 10. The upper portion of the plate 10 is provided with a U-shaped opening 14 to register with a slot 15 in the arm 11, the arm tapering outwardly from the recess or slot, as at 16.

Secured laterally to the bracket portion 8 is a coupling member 17 which intersects the gas hose or tubing 6 and within the coupling member is a suitable form of valve 18 controlled by a spring urged plate 19, which in turn is controlled by a lever 20 extending outwardly therefrom. When the valve controlling the opening through the coupling and hose is open, the lever 20 is held by the registering openings 14 and 15 of the members 10 and 11, against the tension of the spring urged plate 19, as shown in Figs. 1 and 2.

As shown in Fig. 1 the attachment is mounted on the lever arm 7 of a vulcanizer so that the enlarged portion 12 of the arm 11 is immediately above the safety valve extension 21 of the vulcanizer. The outer end of the extension is closed by a soft metal cap 22 and when excess steam collects within the vulcanizer, the steam blows off said cap and escapes. With the improved attachment, when steam thus escapes, it bears against and pivots the arm 11, releasing the lever 20 which slides over the downwardly inclined edge 16 and through the recess 14 and the valve 18 is thereby closed by the spring urged

plate 19. In this manner the supply of gas is automatically shut off and the work within the vulcanizer is protected from being destroyed by dry heat.

5 From the foregoing description it will be seen that the improved safety valve attachment for dental vulcanizers is of very simple and novel construction and is well adapted for the purpose set forth.

10 What I claim as my invention is:

1. An attachment for a dental vulcanizer having a safety valve opening into the atmosphere and a fuel line, said attachment comprising a fuel cut-off intersecting the fuel line, and exteriorly positioned means operable by steam escaping to the atmosphere from the safety valve for closing said fuel cut-off.

2. A dental vulcanizer fuel line control, comprising a fuel line valve, a pivotal control lever having an enlarged portion positioned within the path of escaping steam from a dental vulcanizer safety valve, an operating rod extending from the valve, and latch mechanism associated with said control lever for engaging a portion of said operating rod and adapted to automatically release the same upon a movement of the control lever in one direction occasioned by the pressure of escaping steam thereagainst.

20 30 In testimony whereof, I affix my signature.
BYRON H. ABERT.
